N. G. MORGAN

END GATE FASTENER

Filed March 24. 1927

2 Sheets-Sheet 2

UNITED STATES PATENT OFFICE.

NORRIS G. MORGAN, OF GALVA, ILLINOIS.

END-GATE FASTENER.

Application filed March 24, 1927. Serial No. 177,864.

This invention relates to end-gate fasteners for use with vehicle bodies having hinged drop end-gates.

It is an object of this invention to provide an end-gate fastener of simple rugged construction that may be readily operated to drop the end-gate and that is self-locking when the end-gate is closed.

It is a further object of this invention to provide an end-gate fastener adapted to maintain the end-gate in tightly closed position without additional locking means and capable of quick action in opening the end-gate.

Other and further important objects of this invention will be apparent from the disclosures in the specification and the accompanying drawings.

This invention (in a preferred form) is illustrated in the drawings and hereinafter more fully described.

On the drawings:

Figure 1 is a rear elevational view of an end-gate fastener shown in connection with a truck body.

Figure 2 is a fragmentary enlarged elevational view of the device.

Figure 3 is a sectional view taken on line III—III of Figure 2.

Figure 4 is a fragmentary top plan view of the device applied to a slightly modified type of body.

Figures 5, 6, 7 and 8 are fragmentary elevational views showing different positions of the device in operation.

Figure 9 is a fragmentary rear elevational view of a modified form of the device.

Figure 10 is a fragmentary side elevational view of the same.

Figure 11 is a fragmentary top plan view of the same.

As shown on the drawings:

The reference numeral 1 indicates a body portion of a motor truck, said body portion having a rear wall 2 provided with an end-gate, 3. It will be understood that the device embodying the principles of my invention is equally applicable to other styles of truck bodies, boxes, containers of various sorts, and the like.

As shown, the end-gate 3 is hingedly connected at its lower edge to a bottom cross piece 4 by means of hinges 5. When closed,

the end-gate 3 lies snugly against the outer face of the rear wall 2 (Figures 1 to 3 inclusive) to form a tight joint. As shown in Figures 4 to 10 inclusive the end-gate 3 extends the full length of the rear of the truck body and in closed position lies against the rear edge of the side walls 6. In either form of construction of end-gate, the end-gate fastener of my construction is equally applicable.

Said end-gate fastener comprises a U-shaped lever 7, having a straight intermediate portion 8 extending substantially the full length of the end-gate 3 and secured thereto by means of bands 9 in parallel adjacent relation to the upper edge of said end-gate 3. Said bands 9 are provided with sockets 10 in which the lever 7 is mounted for swiveling movement. Said lever 7 is further formed (Figures 1 to 8 inclusive) with arms 11 normally extending downwardly and lying in the same plane with the intermediate portion 8. The extremities of said offset arms 11 are turned outwardly in the same plane to provide stub arms 12, to each of which is secured one end of a chain 13. The other end of each of the chains 13 is detachably secured to a hook 14 fastened to the upper edge of a longitudinal partition 15 (Figures 1 to 3 inclusive) or to the upper edge of the side wall 6 (Figures 4 to 8 inclusive) at a point substantially on a level with the lever intermediate portion 8. A sheath 16 encloses each of the offset arms 11 for a distance slightly less than their entire length. Said sheath 16 is preferably formed of sheet metal bent about each of the arms 11 and provided with an extension 17 forming a U-shaped groove 18. The stub arms 12 extend through one wall of the sheath 16 into the trough 18 and are fastened in the opposite wall of said extension 17. The chains 13 accordingly lie in the trough 18, in normal position, parallel to the arms 11, and are trained over the upper edges 19 of said extensions 17. The upper edges 19 of said sheath extensions 17 lie below the horizontal level of the axis of the lever portion 8 for all positions below the horizontal of said offset arms 11 for a reason that will later become apparent. The upper corners of the end-gate 3 are notched as at 20 (Figures 1 to 8 inclusive) to provide a passage for the

chain 13 and also to permit free swinging movement of the offset arms 11.

As shown in Figures 5 to 8 inclusive, the end-gate 3 is lowered by manually raising the offset lever arms 11 to a point above the horizontal level of the intermediate portion 8 of the lever 7 and the hooks 14. During the movement of the offset arms 11 to horizontal position, the end-gate 3 remains closed, but as soon as the arms 11 are raised slightly above the horizontal level or dead point, (Figure 7) the end-gate 3 starts to open and from then on outward pressure against said end-gate 3 or continued manual raising of the arms 11 will effect quick opening action, until the end-gate 3 lies in horizontal position and the lever arms 11 and chains 13 lie in the same straight line. It should be noted that the swinging movement of the lever arms 11 is in opposite direction to that of the end-gate 3 upon its hinges 5, and that a self-locking action is obtained when the lever arms 11 are swung from horizontal position down into vertical position. It should further be noted that the upper edges 19 of the sheath extensions 17 lie below the horizontal level of the axis of the lever's intermediate portion 8 for all positions of the offset arms 11 between horizontal and closed vertical position. As the offset lever arms 11 move from down position (Figure 5) to horizontal position (Figure 6) the edges 19 accordingly move in an arc downwardly and away from the end-gate 3, thus increasing the tension on the chains 13 until the horizontal position of the lever arms 11 is reached. This tension is taken care of by the resiliency of the straight portions 30 of the lever 7 extending beyond the bands or mountings 9. There is accordingly no tendency for the end-gate fastener to joggle loose and open the end-gate 3 accidentally. The end-gate 3 remains tightly closed for any position of the lever arms 11 below the horizontal level of the lever's intermediate portion 8.

In Figures 9 to 11 inclusive there is shown a slightly modified form of end-gate fastener comprising a lever 21 having a straight intermediate portion 22 swivelly mounted in sockets 23, and offset arms 24 provided with inwardly turned stub arms 25. Between said offset arms 24 and the intermediate portion 22 there are formed arcuate portions 26 over which chains 27 are adapted to be trained. The arcuate, or curved portions 26 lie below the horizontal level of the lever's intermediate portion 22 in the same way as the sheath edges 19, above described. Each of said chains 27 is secured at one end to a stub arm 25 and at the other end to a pin 28 adjacent the top edge of a side board 6. The offset arms 24 in this modified form of end-gate fastener do not lie in the same plane with the intermediate lever portion 22, but

are slightly inclined, when in normal position, downwardly toward the end gate 3. The action of this modified form of end-gate fastener is substantially the same as above described.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. An end-gate fastener comprising a lever adapted to be swivelly mounted with its axis parallel to and adjacent the upper edge of an end-gate and having offset ends, chains adapted to be secured to the extremity of each of said ends and to fixed supports, and means constraining a portion of each of said chains below said lever axis to lie parallel to said offset ends in normal position.

2. An end-gate fastener, comprising a bent lever having an intermediate portion adapted to be swivelly secured along the upper edge of an end-gate with its axis in parallel relation thereto and end portions at right angles to said intermediate portion normally extending downwardly, chains adapted to be secured to a fixed support adjacent said upper edge and to the extremities of said lever ends, and means lying below said lever axis when said end-gate is closed over which said chains are adapted to be trained.

3. An end-gate fastener for use with vehicle bodies having hinged end-gates, comprising a U-shaped lever, the intermediate portion of said lever being adapted to be swivelly secured parallel and adjacent to the upper edge of said end-gate, and the end portions of said lever normally extending parallel and adjacent to the ends of said end-gate, chains each adapted to be fastened at its upper end to the vehicle body and at its lower end to the free extremity of a lever end portion, and means lying below said lever intermediate portion providing edges over which said chains are adapted to be trained in all positions of said lever end portions below said intermediate lever portion, whereby said end-gate remains closed until after said lever end portions are raised above said intermediate portion.

4. An end-gate fastener for use with vehicle bodies having hinged drop end-gates, comprising a lever member having normally downwardly extending offset arms at each end thereof and an intermediate straight portion, means swivelly securing said intermediate portion to said end-gate along the upper edge thereof, chains joining the free extremity of each of said offset arms to the vehicle body, and means causing portions of

25

said chains to lie parallel to said offset arms so long as said arms are below the intermediate portion of said lever member.

5. An end-gate fastener, comprising a lever arm adapted to be secured to an end-gate for swinging movement about an axis parallel to the upper edge of said end-gate, flexible means joining the free end of said lever arm to a fixed support on a level with 10 said axis, and means for effecting a training of said flexible means at a point below said axis so long as the lever arm extends below said axis.

6. An end-gate fastener, comprising a lever arm adapted to be secured for swinging movement about an axis parallel to the upper edge of said end-gate, flexible means secured to the free end of said lever arm, fixed anchoring means for the other end 20 of said flexible means, and means forming a part of said lever providing an edge over which said flexible means is normally trained, said edge providing means lying be-

low said axis for all positions of said lever arm below said axis.

7. An end-gate fastener for an end-gate pivotable about its lower edge, comprising a lever having normally downwardly extending offset ends and an intermediate portion adapted to be swivelly mounted 30 in parallel adjacent position to the upper edge of said end-gate, flexible means connecting the extremities of said lever ends to a fixed point substantially on a level with said lever intermediate portion, and means 35 forming a part of said lever over which said flexible means are normally trained, said means lying below the horizontal level of said fixed point for all positions of the offset lever arms between horizontal and downwardly extending vertical position.

In testimony whereof I have hereunto subscribed my name at Chicago, Cook County, Illinois.

NORRIS G. MORGAN.
